CLAIM

The ornamental design for a box for a compact disk and a digital video disk, as shown and described.

DESCRIPTION

FIG. 1 is an elevation of one side of the box for a compact disk and a digital video disk;

FIG. 2 is an elevation of the side opposite that shown in FIG. 1;

FIG. 3 is an end elevation of one end of FIG. 1;

FIG. 4 is an end elevation of the end opposite that shown in FIG. 3;

FIG. 5 is a vertical elevation of one edge of FIG. 1;

FIG. 6 is a vertical elevation of the edge opposite that shown in FIG. 5;

FIG. 7 is a perspective view of FIG. 1 when closed; and, FIG. 8 is perspective view of FIG. 1 when opened.

The broken line features shown on the right front edge of the box for a compact disk and a digital video disk in FIGS. 1 and 7 are for illustrative purposes only and forms no part of the claimed design.
